UNITED STATES PATENT OFFICE.

WILLIAM H. HARRISON, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,287,009.

Specification of Letters Patent.

Patented Dec. 10, 1918.

Application filed May 9, 1918. Serial No. 233,449.

To all whom it may concern:

Be it known that I, WILLIAM H. HARRISON, a citizen of the United States, residing at Brooklyn, in the county of Kings, State 5 of New York, have invented certain new and useful Improvements in Telephone-Exchange Systems, of which the following is a full, clear, concise, and exact description.

This invention relates to telephone exchange systems, and more particularly to 10 such systems employing trunk circuits over which connections between telephone lines terminating at different switchboards may be made.

15 The object of this invention is to provide improved signaling means for systems of this character.

In accordance with this invention, a trunk circuit having at its incoming end a signaling 20 device operatively responsive to signaling current applied to the trunk circuit when connection is made therewith at the outgoing end, is provided with means effective when connection is made with the incoming end to operatively disconnect the 25 signaling device from the trunk circuit, and with means effective when disconnecting from the outgoing end to operate the signaling device.

30 For a more complete understanding of this invention, reference should be had to the following description, considered in connection with the accompanying drawing illustrating one embodiment thereof.

35 As shown in the drawing, a trunk circuit A extends from a first switchboard X to a second switchboard Y. At the switchboard X there is located a cord circuit B, by means of which connection may be made 40 between a telephone line (not shown) terminating at switchboard X and the trunk circuit A. A cord circuit C provided at the switchboard Y may be employed for connecting the trunk circuit A with an extension line represented by the jack D, or with a trunk circuit (represented by jack E) extending to a central office. The extension telephone line D and the trunk circuit E are preferably of the types disclosed in the 45 patent to H. L. Darrah, No. 1,232,507, with this difference, that the sleeve contact of the jack of the extension line D has no ground connection and the sleeve contact of the

jack of the trunk circuit E has a ground instead of a battery connection. 55

The cord circuit C may also be employed to interconnect extension lines or to connect an extension line with the central office trunk circuit. The apparatus shown to the left of the dotted line, 2—2, may be located 60 at the switchboard X, and that shown to the right of the dotted line 3—3, at the switchboard Y.

The operator at switchboard X desiring to establish a connection with or through 65 the switchboard Y may insert plug 5 of the cord circuit B into jack 6 of the trunk circuit A, whereupon lamp 7 is lighted and relay 8 operated over a circuit from battery through the normal contact of the listening 70 key 9, contact of supervisory relay 10, lamp 7, sleeve contacts of the plug 5 and the jack 6 and the winding of relay 8 to ground. Relay 8, in operating, causes the operation of a slow-release relay 11, the function of which 75 will more fully hereinafter appear. Relay 12 also operates upon the connection of the plug 5 with the jack 6. The operator may now actuate ringing key 13 to cause the operation of relay 15 over a circuit from a 80 source of ringing current 16 through the lower alternate contact of ringing key 13, ring contacts of the plug 5 and the jack 6, condenser 17, winding of relay 15, tip contacts of the jack 6 and the plug 5, contact of 85 relay 12 and the upper alternate contact of ringing key 13 to ground. Relay 15, in operating, causes the operation of relay 18, which connects a second source of ringing current 90 19 in circuit with and operates an electro-magnetic drop 20, the shutter 21 of which falls to furnish a signal. The restoration of the ringing key 13 to normal position causes the release of relays 15 and 18 and the disconnection of the source 19 from the trunk 95 circuit. The operator at switchboard Y, observing the operated condition of the drop 20, may insert plug 30 of the cord circuit C into jack 31 of the trunk circuit A, whereupon a slow-release relay 32 operates over 100 a circuit from battery through the winding of relay 32 and local contact 33 of the jack 31. After inserting the plug into the jack, the operator may restore the shutter 21 of the drop to its normal position. Relay 34 105 of the cord circuit C, and relay 35 of the

trunk circuit A do not operate. Relay 32, in operating, connects a marginal relay 36 in bridge of the trunk circuit A, and establishes a short circuit about the winding of the drop 20. This short circuit may be traced from the point 37 through the normal contact of the slow-release relay 38 and contact 39 of relay 32 to the point 40. The drop 20, by being short-circuited, is thereby operatively disconnected from the trunk circuit, and is prevented from operating after its shutter has been restored by the operator. With this short circuit about the drop, the drop is not operated by currents induced in the left-hand windings of repeating coil 41, resulting from the closure and opening of circuit including the right-hand windings of this repeating coil.

The connection of the marginal relay 36 in bridge of the trunk circuit causes the operation of a trunk relay 42 over a circuit from battery through the lower right-hand winding of repeating coil 43, lower normal contact of relay 18, lower left-hand winding of repeating coil 41, winding of relay 36, contact 44 of relay 32, upper left-hand winding of repeating coil 41, upper normal contact of relay 18, upper right-hand winding of repeating coil 43 and both windings of relay 42 to ground. Trunk relay 42, in operating, causes the operation of relay 45, which connects relay 46 in bridge of that end of the trunk circuit which terminates at the switchboard Y. Supervisory relay 10 is thereupon operated over a circuit from battery through the lower winding of retardation coil 48, winding of supervisory relay 10, lower normal contact of ringing key 13, ring contacts of the plug 5 and the jack 6, lower left-hand winding of repeating coil 43, lower contact of relay 45, winding of relay 46, upper contact of relay 45 and the normal contact of relay 46 to ground. Supervisory relay 10, in operating, causes the effacement of the supervisory lamp 7 which may serve as a signal to the originating operator that the distant operator has answered. The operator at switchboard X may then actuate listening key 9 to connect the telephone set with the cord circuit B. Relay 46 also operates, establishing a short circuit for the lower winding of relay 42, thereby reducing the resistance in circuit with the marginal relay 36 which now operates. Upon the operation of relay 46, the energizing path for relays 10 and 46 from the point 22 then continues to ground by way of the upper left-hand winding of repeating coil 43, tip contacts of the jack 6 and the plug 5, the contact of relay 12, upper normal contact of ringing key 13 and the upper winding of retardation coil 48. Relay 36, in operating, establishes operating circuits for slow-release relay 38 and lock-

up relay 50. Relay 50, in operating, establishes a locking circuit for itself from battery through its winding and right-hand alternate contact and contact 33 to ground. 65

Relay 38, in operating, opens the short circuit of resistance 23, which is thereupon included in shunt of the winding of the drop 20. This resistance is low enough to prevent the operation of the drop upon the discharge of either of the condensers 24 or 25. The drop, therefore, remains operatively disconnected from the trunk circuit. 70 75

The operator at switchboard Y may now actuate listening key 51 to connect the operator's telephone set with the trunk circuit. Since the operator's telephone set at the switchboard X is already connected in circuit, the two operators may converse. If connection is to be established with an extension line, the operator at switchboard Y may insert plug 52 into the jack D, and may then actuate a ringing key (not shown) to connect with the extension line ringing current for operating the usual call bell. Upon response of the subscriber on an extension line, the line circuit is closed in the usual manner, whereupon the annunciator 53 is actuated to furnish a signal indicating to the operator that the subscriber has responded. This annunciator 53 furnishes a signal while the subscribers are talking, and does not display a signal when the subscriber has restored the receiver to the switchhook. 80 85 90

If connection is to be established with a line terminating at a central office (not shown) the operator at switchboard Y may then insert the plug 52 into the jack E, whereupon relays 34 and 35 operate in parallel by way of the grounded sleeve contact of the jack of trunk circuit E. The operation of these two relays disconnects battery 100 for talking purposes from both the trunk and the cord circuit. As is usual when connection is established over a central office trunk circuit between a private branch exchange telephone line and a central office 105 telephone line, battery for talking purposes is furnished from the central office. The operation of relay 34 connects retardation coil 54 in bridge of the talking strands of the cord circuit, and relay 35, in operating, 110 connects a resistance 55 in bridge of the talking conductors of the trunk circuit, thereby establishing a circuit for the usual line relay connected with the central office 115 end of the trunk circuit. 120

If the operator at switchboard Y, after inserting plug 30 into the jack 31, does not operate the listening key 51, the operator at switchboard Y may desire to re-ring the operator at switchboard Y. This may be done by withdrawing the plug 5 from, and then reinserting it in, the jack 6. Upon the withdrawal of the plug from the jack, relay 125

46 releases its armature, thereby opening the short circuit about the lower winding of relay 42. The resistance in circuit with marginal relay 36 is thereby increased, causing 5 the release of this relay 36. Upon the release of relay 36, the drop 20 is energized over a circuit from battery through the left-hand lower winding of repeating coil 43, lower normal contact of relay 18 and lower 10 left-hand winding of repeating coil 41, winding of the drop 20, alternate contact of slow-release relay 38, left-hand alternate contact of relay 50, normal contact of relay 36 and contact 33 to ground. The energization 15 of drop 20 causes the attraction of the armature of the drop, which releases the shutter 21 to furnish a signal. The closure of this operating circuit of this drop 20 is but momentary, for relay 38, which is of the 20 slow-release type, begins to release its armature immediately upon the release of the marginal relay 36. Upon the withdrawal of the plug 5 from the jack 6, relay 8 is de-energized, and relay 26 is energized over a 25 path from battery through the normal contact of relay 8, winding of relay 26, normally closed contact of the jack 6, upper left-hand winding of the repeating coil 43, upper contact of relay 45 and the normal 30 contact of relay 46 to ground. Since relay 11 is of the slow-release type, the lower contact of relay 26 is closed before the lower alternate contact of relay 11 is opened, whereby a locking circuit for relay 11 is 35 completed. The lighting of the lamp 27 to furnish a false signal is thereby prevented. The reinsertion of the plug 5 within the jack 6 causes the energization of relay 46, which again short-circuits the lower winding 40 of relay 42, whereupon marginal relay 36 operates. The slow-release relay 38 thereupon operates.

At the conclusion of the conversation which may have been between two operators 45 or between two subscribers, either operator may disconnect before the other. If the operator at the central office X is the first to disconnect, the withdrawal of the plug 5 from the jack 6 causes the deenergization of 50 relays 8 and 46, and the energization of relay 26. The deenergization of relay 46 causes marginal relay 36 to release its armature, as before described, to momentarily close an operating circuit for the drop 20, 55 which permits its shutter 21 to fall to display a disconnect signal. This shutter 21 may be restored to its normal position before the operator at the switchboard Y withdraws the plug 30 from the jack 31. In 60 withdrawing the plug 30 from the jack 31, condenser 28 may be discharged, or a battery circuit including the right-hand windings of repeating coil 41 may be opened or closed. In either event, the resulting flow of

current through the repeating coil windings induces a current in the left-hand windings thereof, whereupon the condensers 24 and 25 may discharge. The drop 20, therefore, remains operatively disconnected from the trunk circuit until after the condensers 70 have been discharged, in order that there may be no false operation of the drop. The operative disconnection of the drop 20 from the trunk circuit is thus maintained, due to slow-release relay 32, which, for an appreciable time after the disconnection of the plug from the jack, holds closed the shunt circuit which for a time includes the resistance 75 23. Upon the removal of the plug 30 from the jack 31, contact 33 is opened, 80 whereupon relay 32 begins to release its armatures. Due to the slow release of this relay 32, the shunt circuit about the winding of the drop 20 is not removed until after the condensers have discharged and the talking 85 circuit has assumed its normal condition.

Should a call originate at the switchboard Y and connection for completion over the trunk circuit A, the insertion of the plug 30 into the jack 31 causes the operation of 90 relay 32. Relay 36 is thereby bridged across the talking strands of the trunk circuit, whereupon relay 42 operates over a circuit from battery through the lower right-hand winding of repeating coil 43, lower normal 95 contact of relay 18, lower left-hand winding of repeating coil 41, winding of relay 36, contact 44 of relay 32, upper left-hand winding of repeating coil 41, upper normal contact of relay 18, upper right-hand winding 100 of repeating coil 43 and the two windings of relay 42 to ground. Relay 42, upon operating, causes the energization of relay 45. Upon being energized, relay 45 causes the operation of relay 26 over a circuit from battery through the normal contact of relay 8, winding of relay 26, normally closed contact of the jack 6, upper left-hand winding of repeating coil 43, upper contact of relay 45 and the normal contact of relay 46 105 to ground. Relay 26, in operating, completes a circuit over which the lamp 27 is lighted, to furnish a signal to the operator at the switchboard X.

The operator at the switchboard X, upon 110 observing the lighted condition of the lamp 27, inserts the plug 5 into the jack 6, whereupon relay 8 operates and relay 26 releases, effacing the lamp 27. Relay 8, in operating, causes the operation of slow-release relay 11 115 120 as before described. Relay 46 now operates and short-circuits the lower winding of relay 42, thereby permitting the operation of relay 36. Relay 36, in operating, causes the operation of slow-release relay 38 and lock-up relay 50. The latter, in operating, closes a locking circuit for itself through its right-hand alternate contact and contact 33 of the

jack 31. Supervisory relay 10 also operates upon the insertion of the plug 5 in the jack 6 to prevent the lighting of the supervisory lamp. The operators may actuate the listening keys, whereupon the circuits and apparatus are in talking condition. At the conclusion of the conversation, the operators withdraw the plugs from the jacks to restore all apparatus to normal condition. If the 10 operator at switchboard Y disconnects before the other operator, the withdrawal of the plug 30 from the jack 31 causes the release of relays 32, 38, 50, 36 and 42. Relay 42, in releasing, causes the release of relay 15 45 followed by the release of relays 46 and 10, whereupon the supervisory lamp 7 lights to furnish a disconnect signal to the operator at switchboard X. Since relay 38 is now 20 released and its alternate contact is open, there will be no false operation of the drop 20 upon the withdrawal of the plug 5 from the jack 6.

What is claimed is:

1. A telephone exchange system comprising 25 a trunk circuit extending from a first to a second switchboard, a link circuit at the first switchboard connected with the trunk circuit, a signaling device at the second switchboard normally operatively associated with the trunk circuit, a source of 30 signaling current, means in the link circuit for connecting the source of signaling current with the trunk circuit for causing the operation of the signaling device, a link 35 circuit at the second switchboard, means responsive to the connection of the second link circuit with the trunk circuit for operatively disconnecting the signaling device therefrom, and means responsive to the disconnection of the first link circuit from the 40 trunk circuit for operatively associating the signaling device with the trunk circuit and for causing the operation thereof.

2. A telephone exchange system comprising 45 a trunk circuit extending from a first to a second switchboard, a link circuit at the first switchboard connected with the trunk circuit, a signaling device at the second switchboard normally operatively associated with the trunk circuit, a source of 50 signaling current, means in the trunk circuit for connecting the source of signaling current with the trunk circuit for causing the operation of the signaling device, a link circuit at the second switchboard, a normally 55 open shunt circuit for the signaling device, a relay energized upon the connection of the second link circuit with the trunk circuit for establishing the shunt circuit about the signaling device, and a relay responsive to the disconnection of the first link circuit 60 from the trunk circuit for completing an operating circuit through the signaling device.

3. A telephone exchange system comprising 65 a two-conductor trunk circuit extending from a first to a second switchboard, a link circuit at the first switchboard connected with the trunk circuit, a signaling device at the second switchboard normally operatively 70 associated with the trunk circuit, a source of signaling current, means in the link circuit for controlling the connection of the source of signaling current in circuit with the two conductors of the trunk circuit and the signaling device thereby to operate the signaling device, a link circuit at the second switchboard, an operating circuit for the signaling device including one of the conductors of the trunk circuit, means responsive 75 to the connection of the second link circuit with the trunk circuit for partially establishing the operating circuit, and means responsive to the disconnection of the first link circuit from the trunk circuit for completing the partially established operating circuit.

4. A telephone exchange system comprising 80 a two-conductor trunk circuit extending from a first to a second switchboard, a link circuit at the first switchboard connected with the trunk circuit, a signaling device at the second switchboard normally operatively 85 associated with the trunk circuit, a source of signaling current, means in the link circuit for controlling the connection of the source of signaling current in circuit with the two conductors of the trunk circuit and the signaling device thereby to operate the signaling device, a link circuit at the second switchboard, a relay energized upon the connection of the second link circuit with the 90 trunk circuit, a second relay bridged across the two conductors of the trunk circuit upon the energization of the first relay and operating thereover, a slow-release relay energized upon the operation of the bridged relay, a relay in the trunk circuit responsive 95 to the disconnection of the first link circuit from the trunk circuit for causing the release of the second relay, and an operating circuit for the signaling device completed upon the release of the second relay and including a contact of the slow-release relay.

5. A telephone exchange system comprising 100 a two-conductor trunk circuit extending from a first to a second switchboard, a link circuit at the first switchboard connected with the trunk circuit, a signaling device at the second switchboard normally operatively 105 associated with the trunk circuit, a source of signaling current, means in the link circuit for controlling the connection of the source of signaling current in circuit with the two conductors of the trunk circuit and the signaling device thereby to operate the signaling device, a link circuit at the second switchboard, an operating circuit for the signaling 110

- device including one of the conductors of the trunk circuit, a relay in the trunk circuit responsive to the connection of the second link circuit therewith for partially establishing the operating circuit, and a relay responsive to the disconnection of the first link circuit from the trunk circuit for completing the operating circuit.
6. A telephone exchange system comprising a trunk circuit extending from a first to a second switchboard, a source of signaling current at the first switchboard, means thereat for connecting the source of signaling current with the trunk circuit, a signaling device in the trunk circuit responsive to the connection of signaling current therewith, a link circuit at the second switchboard, means in the trunk circuit responsive to the connection of the link circuit therewith for operatively disconnecting the signaling device from the trunk circuit, and switching means responsive to the opening of the trunk circuit at the first switchboard and coöperating with the second mentioned means for causing the operation of the signaling device.
7. A telephone exchange system comprising a trunk circuit extending from a first to a second switchboard, a link circuit at the first switchboard connected with the trunk circuit, a signaling device at the second switchboard, a source of alternating current, means in the link circuit controlling the connection of the source of alternating current with the trunk circuit for operating the signaling device, a link circuit at the second switchboard, means responsive to the connection of the second link circuit with the trunk circuit for rendering the signaling device non-responsive to alternating current, a source of direct current, and means responsive to the disconnection of the first link circuit from the trunk circuit for connecting the source of direct current in circuit with the signaling device.
8. A telephone exchange system comprising a trunk circuit extending from a first to a second switchboard, a link circuit at the first switchboard connected with the trunk circuit, a signaling device at the second switchboard, a source of alternating current, means in the link circuit controlling the connection of the source of alternating current with the trunk circuit for operating the signaling device, a link circuit at the second switchboard, a relay in the trunk circuit responsive to the connection of a second link circuit therewith for rendering the signaling device non-responsive to alternating current, a source of direct current, and a relay responsive to the disconnection of the first link circuit from the trunk circuit for connecting the source of direct current in circuit with the signaling device to cause the operation thereof.

9. A telephone exchange system comprising a trunk circuit extending from a first to a second switchboard, a link circuit at the first switchboard connected with the trunk circuit, a signaling device at the second switchboard, a source of alternating current, means in the link circuit controlling the connection of the source of alternating current with the trunk circuit for operating the signaling device, a link circuit at the second switchboard, a relay in the trunk circuit responsive to the connection of the second link circuit therewith, a source of direct current, a relay responsive to the disconnection of the first link circuit from the trunk circuit, and an operating circuit for the signaling device and a source of direct current established upon the response of the second relay and including contacts of both relays.
10. A telephone exchange system comprising a trunk circuit extending from a first to a second switchboard, a link circuit at the first switchboard connected with the trunk circuit, a signaling device at the second switchboard, two sources of current of different character, means in the link circuit controlling the connection of one of the sources of current with the trunk circuit for operating the signaling device, a link circuit at the second switchboard, means responsive to the connection of the second link circuit with the trunk circuit for operatively disconnecting the signaling device from the trunk circuit, and means responsive to the disconnection of the first link circuit from the trunk circuit for connecting the other source of current in circuit with the signaling device.
11. A telephone exchange system comprising a trunk circuit extending from a first to a second switchboard, a link circuit at the first switchboard connected with the trunk circuit, a signaling device at the second switchboard, two sources of current of different character, means in the link circuit controlling the connection of one of the sources of current with the trunk circuit for operating the signaling device, a link circuit at the second switchboard, means responsive to the connection of the second link circuit with the trunk circuit, a normally ineffective operating circuit for the signaling device and the other of the two sources of current, and means responsive to the disconnection of the first link circuit from the trunk circuit and coöperating with the other responsive means to render the operating circuit effective for causing the operation of the signaling device.

12. A telephone exchange system comprising a trunk circuit extending from a first to a second switchboard, a link circuit at the first switchboard connected with the trunk circuit, a signaling device at the sec-

ond switchboard, two sources of current of different character, means in the link circuit controlling the connection of one of the sources of current with the trunk circuit for operating the signaling device, a link circuit at the second switchboard, a relay energized while the second link circuit is connected with the trunk circuit, a relay deenergized upon the disconnection of the first link circuit

circuit from the trunk circuit, and an operating circuit for the signaling device and the other of the two sources of current established upon the deenergization of the second relay and including contacts of both relays.

In witness whereof, I hereunto subscribe my name this 3rd day of May A. D., 1918.

WILLIAM H. HARRISON.
